UNITED STATES PATENT OFFICE.

SAUL RITTER, OF NEW YORK, N. Y., ASSIGNOR TO SIMON BRUNER, OF FAR ROCKAWAY, NEW YORK.

DESIGN FOR A DISPLAY CASE.

Application filed August 26, 1927. Serial No. 23,209. Term of patent 3½ years.

To all whom it may concern:

Be it known that I, SAUL RITTER, a citizen of the United States, residing at 128 Fort Washington Ave., New York, county of New York, and State of New York, have invented a new, original, and ornamental Design for a Display Case, of which the following is a specification, reference being had to the accompanying drawing, forming part thereof.

Fig. 1 is a perspective view of a display case with the cover removed showing my new design, and Fig. 2 is a perspective view of the case with the cover thereon.

I claim:

The ornamental design for a display case as shown.

In testimony whereof, I have hereunto subscribed my name this 22d day of August, 1927.

SAUL RITTER.
